CRATING APPARATUS

Emil Anderson, Briarcliff Manor, N. Y.

Application November 1, 1934, Serial No. 751,004

15 Claims. (Cl. 226—14)

This invention relates to crating apparatus and particularly to a machine for automatically assembling and placing or depositing bottles, cans or similar containers in crates.

This mechanism has been particularly developed for handling milk bottles. At the present time the filled and sealed bottles of milk are fed to a platform or support from which they must be manually lifted and deposited in crates. Two men are usually required to perform this work and to handle the output of the bottles from the filling and sealing apparatus.

This invention has for its salient object to provide apparatus for automatically crating filled and sealed containers and for accurately depositing the containers in the crate.

Another object of the invention is to provide means in mechanism of the class described for preventing the crating mechanism from operating in case no crate is disposed in a position to receive the containers.

Another object of the invention is to provide simple, practical and efficient mechanism for crating containers so constructed and arranged that the mechanism can be attached to the standard bottle handling apparatus between the conveyor which discharges the filled containers from the filling and sealing mechanism and the crate feeding means.

Another object of the invention is to provide in mechanism of the character described means whereby the bottles can be inspected for foreign or extraneous matter.

Further objects of the invention will appear from the following specification taken in connection with the drawings which form a part of this application, and in which

Fig. 1 is an elevational view of mechanism constructed in accordance with the invention;

Fig. 2 is a top plan view of the mechanism shown in Fig. 1;

Fig. 3 is an end elevation, partly in section, of the machine shown in Fig. 1;

Fig. 4 is a top plan view on a smaller scale showing the crate feeding and positioning mechanism, parts being shown in section;

Fig. 5 is a detail sectional elevation showing one of the clutches and the control means therefor;

Fig. 6 is a top plan view of the structure shown in Fig. 5; and

Fig. 7 is a detail sectional elevation showing further clutch control means.

The invention briefly described consists of

mechanism adapted for attachment to standard bottle handling apparatus and arranged to receive a plurality of bottles on a platform and to transfer these bottles in groups to crates positioned to receive them. The bottles or containers are fed to the support by the usual conveyor which discharges the filled and sealed bottles and transfer means is mounted on a movable carrier and is arranged to move periodically into engagement with the bottles on the support and to transfer the bottles to a position above a crate section and thereupon to lower the bottles and to deposit them in the section. After one set of bottles has been deposited the crate is permitted to move forwardly to a position in which the next section or division of the crate is so disposed as to receive the next group of containers or bottles. This operation is repeated until all of the compartments or sections of the crate are filled whereupon the next succeeding crate on the crate conveyor will move forward to position its forward compartment in the proper location to receive the next load.

Means is provided in connection with the apparatus to prevent the transfer means from operating in case no crate is in position to receive the load.

Further details of the invention will appear from the following description.

In the particular embodiment of the invention illustrated in the drawings, the mechanism is supported on the side rails 10 and 11 of the crate support. Between these rails runs a chain or belt 12 which operates continuously and feeds the crates periodically when they are not held against movement by one of a plurality of stop members A, B, C or D.

The mechanism was designed particularly for transferring milk bottles from a support 13 to the crate. The support 13 receives the bottles from and is disposed in alignment with an endless conveyor 14 which conveys the bottles to the mechanism from the filling and sealing apparatus. The milk crates or containers are usually provided with four compartments, each compartment having three divisions. For this reason the bottles are fed three at a time and are deposited in successive compartments in the crate which is fed forwardly a distance equal to the width of one compartment after each operation of the transfer mechanism.

The transfer mechanism is mounted on uprights or pedestals 20 and 21 which are clamped to the side rails 10 and 11 and may if desired be made vertically adjustable in the manner illus-

5

trated in Fig. 1. As there shown, the uprights 20 are adjustably mounted in vertical guideways 22 which are secured to the rails and each post or upright 20, 21 has formed at one edge thereof a rack 23 which is engaged by a pinion 24. By rotating the pinion shaft 25 the uprights 20 and 21 will be raised or lowered. This adjustment is provided for the purpose of accommodating the machine for use with containers of different heights, such for instance, pint bottles and quart bottles.

The transfer means consists of a plurality of transfer members 30 which are pivotally mounted on trunnions 31 carried by lugs 32 secured to a 15 pair of endless carrier members or chains 33. The chains are mounted on sprockets 34 and 35 carried by spindles 36 and 37. The spindle 37 is mounted at the free ends of arms or beams 38 which are pivoted on the spindle 36.

20 Each of the transfer members 30 is provided with a plurality of yokes or forks adapted to embrace the necks of the bottles below the upper bead or flange. Each transfer member also has formed thereon on the opposite side of the pivot 25 of the member a heel or tail 39 which acts as a stop to limit the swinging movement of the transfer member when the member is operating to convey or transfer the bottles to a position above the crate. The forks on the transfer member are 30 spaced apart to such an extent as to properly space the bottles for discharge into the crate sections.

In Fig. 1 the chains or carriers 33 have mounted thereon two transfer members. When three 35 bottles have been deposited on the platform 13 the carriers are actuated to move one of the transfer members 30 from its position of rest, shown in dotted lines at E in Fig. 1, to the position F in which it engages the bottles on the platform 40 13 and from the position F to the position G. At this time, in a manner hereinafter described, the arms or beams 38 swing downwardly or in a clockwise direction about the spindle 36 viewing Fig. 1 and the carriers continue to move the 45 transfer members 30 during the downward motion so that the bottles will move downwardly in a vertical plane into the crate or box positioned to receive them. Thus, during one operation of the carriers or chains 33 the transfer member 50 in operation will move from the position E to the position H. However, during the movement from the position G to the position H the arms 38 will swing downwardly to discharge the bottles into the crates.

55 In order to guide and steady the bottles during their downward movement resilient blades or strips 45 and 46 are disposed in the path of movement of the bottles and converge downwardly, as shown in Fig. 1. The blades 45 and 46 are carried by cross members 47 and 48 which extend over the path of movement of the crates and are carried by members 49 secured to upwardly extending pedestals 50 connected to the side frame members 10 and 11. During the downward 60 movement of the transfer member the tail 30 will engage the cross member 47 and swing the transfer member in a clockwise direction viewing Fig. 1, thus withdrawing the forks of the transfer member from engagement with the bottle and 65 permitting the bottles to drop into the crate. This is shown in dotted lines in Fig. 1.

Transfer operating and control mechanism

The transfer mechanism may be driven in any 75 suitable manner and in the embodiment of the

invention shown, a motor M is mounted on a bracket or support 55 which is connected to rearwardly extending portions 56 of the arms 38. The motor shaft 59 has mounted thereon a worm 60 which meshes with a worm gear or wheel 61 5 loosely mounted on a shaft 62. The worm wheel 61 has pins 63 and 64 extending laterally from the side faces thereof.

The spindle or shaft 36 on which the sprocket 34 is mounted has also mounted thereon a 10 sprocket 65 which is connected by a chain 66 to a sprocket 67 secured to a hollow shaft 68 concentric with the shaft 62. A clutch member 70 is fixed to the hollow shaft 68 and is provided with laterally movable spring actuated dogs 71 which 15 are normally held in retracted position by a lug 72 formed on a lever 73 which is mounted on a fixed pivot 74. When the lug 72 engages one of the dogs 71 the dog will be held in retracted position. However, when the lever 73 is raised to the 20 position shown in Fig. 5 the dog engaged thereby will be released and will be positioned in the path of movement of one of the pins 63 carried by the worm wheel 61. The worm wheel rotates continuously when the motor is running and 2 when the lever 73 is raised the rotation of the worm wheel will be communicated to the clutch member 70 and to the hollow shaft 68. This will cause the sprocket 67, chain 66 and sprocket 65 to rotate the carrier shaft 36 and move one of 3 the transfer members from the position E into engagement with the bottles on the platform 13 and to the position G whereupon the arms 38 will swing downwardly at the same time that the transfer member moves from the position G to H. 3

The lever 73 is operated by a link 80 which is connected at 81 to the lever and is normally held in its lower position by means of a spring 82 which encircles the link and engages a fixed abutment 83 at one end and a collar 84 on the 4 link at the other end. The lower end of the link 80 is provided with a slot 85 in which is positioned a pin 86 carried by a lever 87 which is pivoted at 88.

The conveyor 14 which conducts the bottles 4 from the filling and sealing apparatus to the transfer mechanism is disposed in substantial alignment with the platform 13. However, between the conveyor and the platform there is mounted a star wheel 90 having six concaved 5 portions 91 adapted to receive the bottles. The star wheel 90 is mounted on a vertical spindle 92 and will be rotated one-half of one revolution when three bottles or one load of bottles has been deposited on the platform 13. On the under surface of the star wheel 90 are downwardly extending lugs 93 and 94 and each time three bottles have been deposited on the platform one of the lugs will engage and tilt the lever 87 in a clockwise direction viewing Fig. 1. This will cause the 6 pin 86 carried by the lever to raise the link 80, thus lifting the lever 73 and permitting the clutch 70 to connect the hollow shaft 68 to the worm wheel 61.

The frame on which the carrier and transfer 6 members are mounted is pivoted on the shaft 36 and comprises the arms 38 and rearwardly extending portions 56 which are connected by a cross member 100. This frame is tiltable on the axis of the shaft 36 in the following manner: 7 The shaft 62 on which the worm wheel 61 is loosely mounted has connected thereto a clutch member 101 having dogs 102 similar to the dogs 71 on the clutch member 70. The dogs 102 are normally held in retracted position by a lever 103 7

which is actuated in a clockwise direction viewing Fig. 7 by a spring 104. The lever 103 has formed thereon or secured thereto an arm 105 which extends into the path of movement of a 5 lug 106 carried by the clutch member 10. When this member 10 has rotated a predetermined extent it will engage the arm 105 of the lever 103 and swing the lever in an anticlockwise direction viewing Fig. 7 releasing the dogs 102 of the 10 clutch member 101. When these dogs are released they extend into the path of movement of one of the pins 64 carried by the worm wheel 61. Thus, the rotation of the worm wheel will cause the clutch member 101 to rotate which in turn 15 will rotate the shaft 62 on which it is mounted. The shaft 62 has also mounted thereon an eccentric disk or cam 110. The eccentric disk or cam 110 engages a roller 111 carried by an arm 112 which is mounted on a fixed pivot 113 on a bracket 20 or lug 114 carried by one of the posts 20. The arm 112 has a bifurcated or forked upper end 115 which straddles the shaft 62. The rotation of the shaft 62 and the cam or eccentric 110 carried thereby will cause the carrier frame to be tilted downwardly about the shaft 36 since the roller 111 carried by the arm 112 is relatively fixed. The shaft 62 during this tilting movement 25 will move upwardly in the bifurcated end 115 of the arm 112. Thus, as the clutch member 101 is actuated to drive the shaft 62 the disk 110 on the shaft will be rotated and will cause the carrier frame to be tilted on the shaft 36 carrying the bottles or containers supported in the transfer member downwardly to the position shown in 30 dotted lines in Fig. 1. The bottles will be released in the manner hereinbefore described and will drop into the compartment in the crate which is positioned to receive the load.

Crate positioning means

40 As hereinbefore stated, the crates are supported on the guide rails 10 and 11 and are frictionally engaged by a continuously operating conveyor belt or chain 12. In order to properly position the crate to receive the loads from the 45 transfer members a plurality of stop members or lugs A, B, C and D are carried by a shaft 120. The lugs are connected to the shaft by a pin and slot connection 121, as indicated in Fig. 4. Means is provided for tilting the shaft 120 after the 50 compartment disposed in receiving position has been filled. This is accomplished by a link 122 which is pivoted at 123 to the carrier frame or extension 56 of the arm 38. The link 122 is connected at its lower end to an arm 124 fixed 55 to the shaft 120. When the carrier frame is tilted the link 122 will be raised and through the arm 124 will tilt the shaft 120 in a clockwise direction viewing Fig. 3, thus raising all of the stop lugs A, B, C and D. The return of the 60 carrier frame to its initial position will oscillate the shaft 120 in the opposite direction permitting the lugs to return to operative position, but since the crate has been permitted to be fed by the conveyor 12 the lug which formerly positioned 65 the crate in receiving position will be disposed against the side wall of the crate and the crate will be stopped by the next succeeding lug. For instance, after the crate shown in Fig. 4 has received a load in the front compartment the shaft 70 120 will be oscillated to raise the lugs A, B, C and D. This will permit the crate to feed or move forwardly, but since the shaft 120 is oscillated in the opposite direction as soon as the carrier frame is returned to its elevated position, the stop 75 lug A will rest against the side wall of the crate

and the crate will be stopped in position by the lug B which will dispose the second compartment in receiving position. This operation will be repeated after each compartment has been filled.

It will be evident that some means must be provided for positioning the front crate out of alignment with the second crate since after the four compartments of the first crate have been filled all four of the stop lugs will rest against the wall of the crate and these lugs would also rest against the wall of the second crate. In order to prevent this means is provided for shifting the front crate laterally on the supporting rails so that the wall of the crate at the side on which the stop lugs are located will be spaced inwardly from the corresponding wall of the next succeeding crate. This is accomplished by means of a lever 125 mounted on a fixed pivot 126 and having a lug 127 adapted to engage the side wall of the crate disposed at the side of the track at which 15 the stop fingers or lug are located. The lever 125 is normally actuated away from the track or guide rails by a spring 128. Timed means is provided, however, for periodically actuating the lever 125 to push the crate laterally on the guide 20 rails. This means consists of a cam 129 mounted on a shaft 130 to which is secured a gear 131 which meshes with a gear 132 mounted on the spindle 92 of the star wheel 90. The gears are so proportioned that after the star wheel 90 has 25 been rotated two times or, in other words, has deposited four loads of three bottles each in the crate the cam 129 will engage and actuate the lever 125 and push the crate laterally on the side rails. The crate will be held in this position 30 by means of spring actuated lugs 135 slidably mounted in the rail or track 11 and actuated in an upward direction by means of springs 136. The other rail 10 carries springs 137 and 138 which act to position the crate on the rails.

Means is provided for preventing the operation of the transfer mechanism unless a crate is in position to receive the bottles or containers. This is accomplished as follows: The shaft 120 is slidably mounted in brackets 140 and 141 by 45 which it is carried and a spring 142 presses against the front end of the shaft. When a crate is positioned in engagement with one of the fingers or stop lugs A, B, C or D the pressure will cause the shaft 120 to be pressed forwardly to the position shown in full lines in Fig. 1. However, should no crate be engaged by any of the lugs the pressure of the spring 142 is sufficient to shift the shaft 120 longitudinally or to the left 50 viewing Fig. 1. The link 122 which is connected to the arm 124 carried by the shaft 120 is provided with a collar 143. When the shaft is pushed to the left in Fig. 1 the collar 143 will be positioned in the path of movement of a lug 144 formed on or secured to the outer end of the lever 87. Thus, the collar will prevent the tilting of the lever by one of the lugs 93, 94 carried by the star wheel 90 and since the lever cannot be operated the driving mechanism for the transfer means will not function. Thus, no load will 55 be engaged by a transfer member and be fed to discharging position. It is obvious that such a safety provision is very important since unless a crate is in position to receive a load the operation of the transfer mechanism would cause the 60 bottles or containers to be discharged and they would probably be broken and the contents be spilled.

In order to insure the proper engagement of the three bottles on the platform 13 by the trans- 75

fer member 30 a rod 150 is normally positioned in the path of movement of the bottles. The rod is carried by a vertical spindle 151 and is pressed by a spring 152 against the bottles positioned on the platform 13. After the bottles have been engaged by the transfer member and the transfer member moves forwardly the rod will be swung out of the way about the axis of the spindle 151.

Operation

Although in the above description bottles have been mentioned as the articles handled, it will be obvious that the invention is not limited to any such specific use. In the machine illustrated, bottles are fed to the platform 13 by the constantly operating conveyor 14 and as they are fed to the platform they will rotate the star wheel 36. Each time three bottles have been deposited on the platform the transfer mechanism will be actuated by the engagement of one of the lugs 33 or 34 carried by the star wheel with the lever 37. If a crate is in position to receive a load the lever 37 will be tilted causing the link 80 to be pushed upwardly, lifting the lever 73 from its operative position and permitting the dogs 71 to move into the path of rotation of the pin 63 carried by the worm wheel 61. This will cause the hollow shaft 68 to rotate, whereupon the sprocket and chain connection 67, 66, 65 will rotate the shaft 36 causing the chains or carrier members 33 and transfer members 30 to start in operation. One of the transfer members 30 will thereupon move from the position E into engagement with a load of containers or bottles on the platform 13 and will carry these bottles to the position G above the compartment to receive them. When the transfer member has reached the position G the lug 106 on the clutch member 70 will swing the lever 103 (Fig. 7) to the right releasing the dog 102 of the clutch member 101 and permitting the dog to move outwardly into the path of movement of the pin 64 carried by the worm wheel 61. This will clutch the shaft 62 to the worm wheel causing the shaft to be rotated. As this shaft is rotated the eccentric disk or cam 110 by reason of its engagement with the roller 111 will swing the carrier frame downwardly about the axis of the shaft 36. During this downward movement the transfer member will move from the position G to the position H, thus maintaining the bottles or articles supported thereby in a vertical plane during their downward movement. When the transfer member reaches the dotted line position shown in Fig. 1 the tail 39 of the transfer member will engage the cross rod 47 and tilt, thus releasing the bottles. During the downward movement of the bottles they will be steadied and guided by the spring plates 45, 46. The carrier frame and transfer members will move downwardly to discharge position and back to their initial position upon one complete rotation of the shaft 62 and upon the completion of this rotation the lever 103 will cause the dog 102 to be retracted out of the path of movement of the pin 64.

After one load has been deposited in the crate compartment and upon the tilting of the carrier frame the shaft 120 will be oscillated freeing the crate from the stop fingers or lugs. The shaft, however, is immediately returned to its initial position and the crate will be stopped in its feeding movement by the next succeeding lug. For instance, in Fig. 4 after the front compartment has been filled the crate will be released and will be next engaged by the stop lug or finger B.

As hereinbefore described, in order to insure the stopping of the next succeeding crate by the lug A after one crate has been fed the forward crate is shifted laterally after four loads have been deposited therein by the operation of the lever 125 in the manner above explained. In addition to the bottle transferring mechanism above described the device is provided with means by which the bottles can be inspected. Sometimes during the filling and sealing of the bottles one of the bottles will be cracked and the broken pieces will naturally fall to the bottom. Also extraneous or foreign matter may enter the bottle and this matter usually settles to the bottom. In order to enable the operator to detect such foreign matter as rests on the bottom of the bottle a mirror R is supported beneath the path of movement of the bottles from the support 13 to the discharge position above the crate. Since the bottles are suspended from above the bottoms of the bottles can be observed in the mirror and any foreign matter in the bottle can be easily detected. A second mirror R' may be located at the side, as shown in Fig. 3.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. Apparatus for depositing containers in a crate comprising a support, means for feeding containers to said support, means for feeding crates, said support being disposed above the level of the upper ends of the crates, an endless carrier, transfer means thereon for successively engaging the containers on said support and movable in a single plane to feed them to a position above the crate into which they are to be deposited, means controlled by the containers fed to said support for moving said endless carrier and transfer means, and means operable on said endless carrier for lowering the transfer means and depositing the containers in the crate.

2. Apparatus for depositing containers in a crate comprising a support, means for feeding containers to said support, means for feeding crates, a movable carrier, a plurality of successively acting transfer means thereon for successively engaging and successively transferring the rows of containers on said support and feeding them to a position above the crate into which they are to be deposited, means controlled by the containers fed to said support for moving said movable carrier and transfer means, said transfer means being movable in a single plane from receiving position to a position above the crate, means operable on said movable carrier for lowering the transfer means and depositing the rows of containers successively in the crate and means for operating the crate feeding means to feed the crate after each row of containers has been deposited therein to a position to receive the next row of containers.

3. Apparatus for depositing containers in a crate comprising a support, means for feeding containers to said support, means for feeding crates, means engageable with a crate on said crate feeding means for positioning the crate in predetermined positions to receive containers, means for operating said positioning means subsequent to the deposit of each load of containers

in a crate to release the crate and position the crate in its next receiving position, a movable carrier, a plurality of successively acting transfer means thereon for engaging loads of containers 5 on said support and feeding them successively to a position above the crate into which they are to be deposited, means controlled by the containers fed to said support for moving said movable carrier and transfer means, and means operable on 10 said movable carrier for successively lowering the transfer means and depositing the containers in the crate.

4. Apparatus for depositing containers in a crate comprising a support, means for feeding 15 containers to said support, means for feeding crates, means engageable with a crate on the crate feeding means for positioning the crate in predetermined positions to receive containers, means for operating said positioning means 20 subsequent to the deposit of each load of containers in a crate to release the crate and position the crate in its next receiving position, and a plurality of successively acting, positively driven means operable to engage and transport the containers 25 from the support to the crate.

5. Apparatus for depositing containers in a crate comprising a support, means for feeding containers to said support, means for feeding crates, means engageable with a crate on the 30 crate feeding means for positioning the crate in predetermined positions to receive containers, means operable to transfer the containers from the support to the crate, and means including the crate positioning means and operable when a 35 crate is not positioned in any one of said predetermined positions for preventing the operation of said transfer means to deposit containers when no crate is positioned to receive the containers.

6. Apparatus for depositing containers in a 40 crate comprising a support, means for feeding containers to said support, means for feeding crates, means engageable with a crate on the crate feeding means for positioning the crate in predetermined positions to receive containers, 45 means for operating said positioning means subsequent to the deposit of each load of containers in a crate to release the crate and position the crate in its next receiving position, means operable to transfer the containers from the support to the crate, and means including the crate 50 positioning means and operable when a crate is not positioned in any one of said predetermined positions for preventing the operation of said transfer means to deposit containers when no 55 crate is positioned to receive the containers.

7. Apparatus for depositing containers in a 60 crate comprising a support, means for feeding containers to said support, means for feeding crates, a movable carrier, transfer means thereon for successively engaging rows of containers on 65 said support and successively feeding them in a single plane to a position above the crate into which they are to be deposited, means controlled by the containers fed to said support for moving said movable carrier and transfer means, means operable on said movable carrier for lowering the transfer means and depositing the rows of containers, one row at a time in the crate, means for preventing the operation of said transfer means 70 to deposit containers when no crate is positioned to receive the containers and means for operating the crate feeding means to feed the crate after each row of containers has been deposited therein to a position to receive the next row of containers.

75 8. Apparatus for depositing containers in a

crate comprising a support for containers, a crate support, a hinged frame above the container support, a movable carrier on said frame, a plurality of transfer means on said carrier, engageable successively with containers on said container support, means for moving said carrier and successively moving said transfer means from a position above the container support to a position above a crate, and means for swinging said frame, carrier and transfer means downwardly, after each row 10 of containers has been engaged and moved thereby, to discharge the row of containers in the transfer means into the crate.

9. Apparatus for depositing containers in a 15 crate comprising a support, means for feeding containers to said support, means for feeding crates, a movable carrier, a plurality of successively acting transfer means thereon for engaging the containers on said support, one row at a 20 time, and movable in a single plane to feed them successively to a position above the crate into which they are to be deposited, means controlled by the containers fed to said support for moving said movable carrier and transfer means, means operable on said movable carrier for 25 lowering the transfer means and depositing the containers, one row at a time, in the crate, means engageable by the containers as they are being deposited in the crate for guiding and steadyng the containers and means for operating the crate 30 feeding means to feed the crate after each row of containers has been deposited therein to receive the next row of containers.

10. Apparatus for depositing containers in a 35 crate comprising a support for containers, a crate support, a hinged frame above the container support, a movable carrier on said frame, a plurality of transfer means on said carrier, engageable successively with containers on said container support, means for moving said carrier and transfer means from a position above the container support to a position above a crate, means for swinging said frame, carrier and transfer means downwardly to discharge the containers in the transfer means into the crate, and means engageable by said transfer means as it swings 45 downwardly to release the containers therefrom.

11. Apparatus for depositing bottles in a 50 crate comprising a support for the bottles, means for supporting a crate, a movable carrier, a hinged support for said carrier, transfer means pivoted on the carrier, means for moving the carrier to cause the transfer means to engage and hold the bottles on the bottle support, and means operable when the transfer means reaches a position 55 above the crate for swinging the hinged carrier support downwardly to release the bottles and deposit the bottles in the crate.

12. Apparatus for depositing bottles in a 60 crate comprising a support for the bottles, means for supporting a crate, a movable carrier, a hinged support for said carrier, transfer means pivoted on the carrier, means for moving the carrier to cause the transfer means to engage and hold the bottles on the bottle support, and means operable 65 when the transfer means reaches a position above the crate for swinging the hinged carrier support downwardly to release the bottles and deposit the bottles in the crate, and means for tilting the transfer means to release the bottles 70 therefrom.

13. Apparatus for depositing bottles in a 75 crate comprising a support for the bottles, means for supporting a crate, a movable carrier, a hinged support for said carrier, transfer means pivoted

- on the carrier, means for moving the carrier to cause the transfer means to engage and hold the bottles on the bottle support, means operable when the transfer means reaches a position above the crate for swinging the hinged carrier support downwardly to release the bottles and deposit the bottles in the crate, and means engageable by the containers as they are being deposited in the crate for guiding and steadyng the containers.
- 5

14. Apparatus for depositing containers in a crate comprising a support, means for feeding containers to said support, means for feeding crates, means engageable with a crate on the 10
15 crate feeding means for positioning the crate in predetermined positions to receive containers, means operable to transfer the containers from

the support to the crate, and means for shifting a crate laterally on the feeding means, relative to the path of feeding movement thereof, when the crate has been filled with containers.

15. Apparatus for depositing containers in a 5
crate comprising a support, means for feeding containers to said support, means for feeding crates, means engageable with a crate on the 10
15 crate feeding means for positioning the crate in predetermined positions to receive containers, means operable to transfer the containers from the support to the crate, and means controlled by the number of containers fed to the crate for shifting a crate laterally on the feeding means, relative to the path of feeding movement thereof, 15 when the crate has been filled with containers.

EMIL ANDERSON.
